UNITED STATES PATENT OFFICE.

GEORGE WASHINGTON MEYERS, OF RAHWAY, NEW JERSEY, ASSIGNOR TO NATIONAL PNEUMATIC COMPANY, OF NEW YORK, N. Y., A CORPORATION OF WEST VIRGINIA.

CENTRIFUGALLY-OPERATED CIRCUIT BREAKER.

Application filed August 20, 1919. Serial No. 318,773.

To all whom it may concern:

Be it known that I, GEORGE W. MEYERS, a citizen of the United States, residing at Rahway, county of Union, State of New Jersey, have made a certain new and useful Invention in Centrifugally-Operated Circuit Breakers, of which the following is a specification.

This invention relates to centrifugally operated circuit breakers.

The object of the invention is to provide a circuit breaker which is centrifugally operated and which is simple in construction and efficient in operation.

A further object of the invention is to provide a circuit breaker designed to maintain an electric circuit open as long as a part or member is in motion and to automatically close the circuit when said part or member comes to rest.

Other objects of the invention will appear more fully hereinafter.

The invention consists substantially in the construction, combination, location and relative arrangement of parts all as will be more fully hereinafter set forth as shown in the accompanying drawings and finally pointed out in the appended claims.

Referring to the accompanying drawings:

Figure 1 is a view in side elevation of a circuit breaker embodying the principles of my invention.

Figure 2 is a broken detail view in section on the line 2—2 of Figure 1, looking in the direction of the arrows.

Figure 3 is a view somewhat in diagram and parts in section showing the application of a centrifugally operated circuit breaker to the control of an electric circuit.

The same part is designated by the same reference numeral wherever it occurs throughout the several views.

In the operation of various kinds of machinery and devices it is frequently necessary and desirable to control electric circuits according to the speed or the movement of a part or a member. For example it is frequently desirable and necessary to prevent the operation of the throttle valve on a steam locomotive until it is safe for the locomotive to be operated, for instance, until all the doors of the train to which the locomotive is connected are closed. Likewise

it is desirable as a matter of safety to prevent the doors of a street car from being opened so long as the car is in motion, whether the motion be derived from the operation of the propelling motor or from coasting or down-grade operation.

It is among the special purposes of my present invention to provide a circuit controlling device or circuit breaker which is centrifugally operated or controlled and which is effective to maintain open the circuit so long as a part or member is in rotation or movement. In carrying out my invention I employ a rotary carrier or device consisting of the annular disc members 4, 5, placed flatwise against each other and suitably bolted together. These members are formed on their opposed faces with complementary chambers in which are received the annular rings 6, 7 of insulating material which are formed on their opposed faces with complementary spherical seats or recesses 8 in each of which is arranged a contact ball or member 9. The insulating rings 6 encompass an annular ring member 10 of insulating material in which are seated but insulated through each other conductor rings 11, 12. These latter project sufficiently into the spherical seats 8 to permit the contact conductor balls 9 therein to bridge the space between them in certain positions of the carrier when said carrier is at rest. One of the conductor rings as 12 is in electrical connection through conductor 13 with a grounded framework. The other conductor ring 11 is in electrical connection with a pin or bolt 14 extending through the longitudinal bore of an insulating plug or spool 16 which extends into the outer face of the member 4 of the carrier at the centre thereof and the inner end of which is offset from the member 4 by means of a fibre plug 17. The outer end of the pin 14 is formed with a spherical head 18 which is encompassed by a boss 19 forming part of a hanger for a dependent weight 20. The spherical head 18 is held in place in a spherical seat formed in the boss 19 by a cap ring 21 which likewise has formed therein a complementary spherical seat to receive the ball 18. The electric circuit to be completed by the circuit breaker device is connected to the boss 19 as at 22.

The provision of the pendulum weight 20

2
to the boss of which is connected one terminal of the circuit to be controlled permits me to eliminate the commutator ring or device sometimes employed in like situations.

5 By the weighted pendulum device the terminal 22 is permitted to remain in proper position notwithstanding the rotation of the shaft or part to which the carrier member is connected.

10 I have shown a centrifugally operated carrier device connected to the shaft 23 which may be the shaft of a motor or any device upon the movements of which the control of an electric circuit is dependent.

15 In one form of practical application of circuit breaker embodying my invention I have a device employed to control the circuit of a magnet 24 which when energized controls a circuit closer 25 controlling the circuit of a lock mechanism indicated at 26, the details of which form no part of the present invention.

From the foregoing description it will be seen that I provide an exceedingly simple rugged centrifugally operated circuit breaker for circuit control device which is inexpensive to manufacture and efficient in operation and which maintains an electric circuit open as long as the member 23 to which the carrier is connected is in operation but which closes the circuit when the carrier device comes to a state of rest.

A centrifugally operated circuit controlled device embodying my invention is 30 adapted for use in many relations and in connection with various machines where safety of operation is desirable to be attained.

Having now set forth the objects and the nature and the construction embodying the 40 principles of my invention, what I claim is new and useful and of my own invention and desire to secure by Letters Patent is:—

45 1. In a centrifugally operated circuit breaker, the combination with a rotating shaft, of a member mounted on said shaft to rotate therewith, said member having a circumferentially extending channel therein, an insulation ring in said channel, conductor rings carried in said insulation ring, said insulation ring being provided with pockets in which said conductor rings are exposed for electrical contact and means in said pockets for bridging said conductor rings.

50 55 2. In a centrifugally operated circuit breaker, the combination with a rotating shaft, of a member mounted on said shaft to rotate therewith comprising a pair of disc members having means to form an annular chamber, a pair of insulation rings in said chamber having spherical pockets, separated conductor rings carried in said insulation rings and exposed in said pockets and means for establishing circuit connection between said conductor rings when

said shaft is stationary and for breaking said connection when said shaft is revolving.

3. The combination with a pair of discs each provided with an annular groove in the inner face thereof and a current conducting member located in said groove but insulated from the disc, means for securing said discs together, said grooves co-operating to form an annular channel with the conducting members out of contact with each other, of a plurality of metal balls loosely enclosed by said discs in said annular channel, and co-operating means carried by said discs for enclosing each individual ball.

4. The combination with a rotary shaft, 75 of a centrifugally operated circuit control device mounted thereon to rotate therewith including separated contacts included in an electric circuit, a circuit conducting member in circuit connection with one of said contacts and mounted to rotate with said shaft, said conducting member terminating in a ball, a socket for said ball and means for conducting current to said socket.

5. The combination with a rotary shaft, 90 of a centrifugally operated circuit control device mounted thereon to rotate therewith including separated contacts included in an electric circuit, a circuit conducting member in circuit connection with one of said contacts and mounted to rotate with said shaft, said conducting member terminating in a ball, a socket for said ball and means for conducting current to said socket, and means for maintaining said socket connection stationary when said shaft is rotated.

6. The combination with a rotary shaft, 100 of a centrifugally operated circuit control device mounted thereon to rotate therewith including separated contacts included in an electric circuit, a circuit conducting member in circuit connection with one of said contacts and mounted to rotate with said shaft, said conducting member terminating in a ball, a socket for said ball, and means for conducting current to said socket, and a weight suspended from said socket connection.

7. In a centrifugally operated circuit breaker, the combination with a rotating 115 shaft, of a member mounted on said shaft to rotate therewith, said member having a circumferentially extending channel therein, annular insulating members within said channel provided with spherical seats, circumferentially extending conductors embedded in said insulating members, but exposed in said seats, means for bridging said conductors freely carried within said spherical seats whereby electrical connection between said conductors is disrupted upon slight movement of said circuit breaker.

In testimony whereof I have hereunto set my hand on this 18th day of August, A. D. 1919.

GEORGE WASHINGTON MEYERS.
